(57) **CLAIM**

The ornamental design for a set of toy bunny Easter egg ears, as shown and described.

DESCRIPTION

FIG. 1 is a front elevational view of the set of toy bunny Easter egg ears, the matter shown in stippled lines does not form part of the claimed design;

FIG. 2 is a side elevational view thereof;

FIG. 3 is a rear elevational view thereof;

FIG. 4 is a side elevational view thereof;

FIG. 5 is a top plan view thereof; and,

FIG. 6 is a side elevational thereof, showing a second position of the ears.
